UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS.

CAR-DOOR-OPERATING MECHANISM.

1,185,057.

Specification of Letters Patent. Patented May 30, 1916.

Application filed September 2, 1915. Serial No. 48,580.

To all whom it may concern:

Be it known that I, ARGYLE CAMPBELL, a citizen of the United States, residing at Chicago, in the county of Cook and State of Illinois, have invented a certain new and useful Improvement in Car-Door-Operating Mechanism, of which the following is a full, clear, concise, and exact description, reference being had to the accompanying drawings, forming a part of this specification.

This invention relates to improvements in car door operating mechanism.

An object of the invention is to provide a simple and efficient door operating mechanism for hopper cars, so arranged that the longitudinally extending shaft from which the links extend to the doors is operated by a transversely extending shaft from the side of the car.

In the drawing forming a part of this specification, Figure 1 is a side elevation of approximately one-half of a hopper car showing my improvements in connection therewith. Fig. 2 is a transverse sectional view of the car shown in Fig. 1, the left hand portion of Fig. 2 being taken substantially on the line $x-x$ of Fig. 1 and the right-hand half on the line $y-y$ of Fig. 1, the hopper doors, however, being shown in end elevation. Fig. 3 is a transverse sectional view taken substantially on said section line $x-x$, but on a larger scale than the section of Fig. 2, in order to more clearly illustrate the parts. Fig. 4 is a detail sectional view taken longitudinally of the car substantially on the line 4-4 of Fig. 5. Fig. 5 is a detail sectional view taken transversely of the car, substantially on the line 5-5 of Fig. 4. Fig. 6 is a horizontal top plan view of the supporting brackets, chain winding drums and shafts, the plane coinciding substantially with that indicated by the line 6-6 of Fig. 3. And Fig. 7 is a detail elevational view illustrating more particularly the construction and arrangement of the operating shaft locking and releasing means.

In said drawing, 10-10 denotes the side walls of a hopper car, the same having inclined end hopper sheets 11, the car, as shown, being provided with four longitudinally arranged hoppers, two on each side of the center sill which is composed of a pair of channels 12-12, each of said hoppers being formed by end hopper sheets 13, out-

wardly and downwardly inclined bottom 55 hopper sheets 14, and swinging hopper doors 15 hinged along their upper edges as indicated at 16 to an angular side sill 17.

The operating mechanism for the doors comprises a longitudinally extending shaft 60 18 located below the built-up girder like center sill, said shaft 18 being rotatably mounted in a plurality of depending brackets 19-19, having upper flanged bases 20 riveted or otherwise secured to the lower 65 flanges of the channels 12-12. As will be understood, each of the brackets 19 has a suitable bearing 21 in which the shaft 18 is supported. Connecting each of the hopper doors 15 with the shaft 18 are link connections which, as shown in the drawing, each comprise an elongated link 22, having a hook 23 at its inner end, a short link 24 pivoted thereto, a second short link 25 pivoted to the link 24, said link 25 being pivoted at its 75 other end as indicated at 26, to an arm 27, formed integrally with a shouldered block 28 fixed to the shaft 18. As clearly indicated in Figs. 2 and 3 the link connections between the swinging doors on opposite sides of the 80 center sill are so arranged that they counter-balance each other, so that when the hopper doors are in closed position the shaft 18 is relieved of any tendency to rotate.

For operating the shaft 18 from the sides 85 of the car, I provide the following arrangement: A transversely extending operating shaft 29 is mounted in brackets 30-30, secured to the channels 12 as clearly indicated in Fig. 5. At its ends the shaft 29 is mounted in bearing brackets 31 secured to the sides of the car and each end of the shaft 29 is squared as indicated at 32. Secured to each end of the shaft 29 is a ratchet wheel 33. In order to lock and release the shaft 95 29 from either side of the car, I have provided two shafts 34 and 134 which extend from side to side of the car and have their ends mounted in suitable bearings carried by the brackets 31. At each end, the shaft 100 34 has secured thereto a pawl or dog 135, which engages and co-operates with the corresponding adjacent ratchet wheel 33. The pawl 135 has a weighted arm 136 so that the pawl is kept normally in engagement with the ratchet wheel under the influence of gravity. On each end of the shaft 134 is secured a locking cam 137 which engage

with the weighted arms 136 of said pawls. As clearly appears from Fig. 7, the pawl and cam castings 135 and 137 are provided with squared portions as indicated at 138—138, said squared portions conforming in size and shape to the squared ends of the shaft 29.

The shaft 29 is round throughout the greater portions of its length and is squared where the same passes through the bearings provided in the brackets 30 and 31. On these squared portions of the shaft 29 are suitable bushings which fit within the corresponding brackets 30 and 31, to thereby permit the shaft to rotate. Mounted on the squared portion 129 of the shaft 29 between the two brackets 30—30 are two chain winding drums 35 and 36, the latter being suitably spaced apart by a spacing sleeve 37. The squared portion 129 of the shaft is provided with suitable bushings 38 in order to form proper bearings in the brackets 30. As clearly appears from Figs. 5 and 6, the drums 35 and 36 extend up between the channel center sills and the lower flanges thereof are cut away as indicated at 39—39 to provide the necessary clearance. By this means I am enabled to obtain a very rigid mounting for the mechanism and also to position it as high as possible without running the operating shaft through the center sill. Directly before the drums 35 and 36, the shaft 18 has secured thereto two spaced drums 40 and 41, each of which is provided with an offset flange 42 to which is secured an eye-bolt 43 by which the chains 44 and 45 are attached thereto, the chain 44 being secured at its upper end to the drum 35 and the chain 45 to the drum 36.

The operation is as follows: Assuming the doors in closed position and the shaft 29 locked against rotation, the operator first moves the locking cam 35 to inoperative position by applying his claw bar or other instrument to the squared portion 138 thereof. Next the operator applies his claw bar to the squared portion 138 of the pawl casting and swings the pawl to inoperative position. Thereafter, the operator applies the claw bar to the squared end of the shaft 29, rotating the latter in a counter clockwise direction, as viewed in Fig. 7. This winds the chain 45 around the drum 36, which causes the shaft 18 to rotate in a counter clockwise direction, thereby releasing the doors. To close the doors, the operating shaft 29 is rotated in a clockwise direction, thereby winding the chain 44 around the drum 35 and causing the rotation of the shaft 18 in a clockwise direction. As will be evident, the operator can manipulate the locking cams, pawls, and shaft 29 from either side of the car, which is an extremely important consideration, particularly where the mechanism is employed on

cars that are run upon trestles where the operators have access to the cars from one side only. Another feature of my improvement is that the same instrument which is used to rotate the shaft 33, such as a claw bar, can be employed to operate the shafts 34 and 134.

From the preceding description, it will be seen that I have provided an efficient door operating mechanism, all the parts of which are compactly arranged, and one which may be operated from either side of the car.

I claim:

1. In a hopper car having two sets of hinged doors on opposite sides of the center thereof, an operating mechanism for said doors including; a single longitudinally extending shaft, link connections between said shaft and all of said doors, an operating shaft extending transversely of the car and operable from the side thereof, and means for operating said longitudinal shaft from the operating shaft comprising a pair of drums on each of said shafts and flexible connections between the drums.

2. In a hopper car having a center sill and hinged hopper doors, an operating mechanism for said doors including; a longitudinally extending shaft mounted below said center sill and supported in brackets secured thereto, connections between said shaft and said doors, an operating shaft extending transversely of the car, a pair of drums on each of said shafts, and flexible connections between said drums.

3. In a car having hinged doors, an operating mechanism for said doors including; a longitudinally extending shaft, connections between said shaft and said doors, a horizontal operating shaft extending at right angles to said longitudinal shaft and located in a plane above the latter, a pair of drums on each of said shafts, a flexible connection from one drum on the longitudinal shaft to one of the drums on the operating shaft and adapted to rotate the longitudinal shaft in one direction and another flexible connection from the second drum on said longitudinal shaft to the second drum on the operating shaft and adapted to rotate the longitudinal shaft in the opposite direction.

4. In a car having a center sill and hinged hopper doors, an operating mechanism for said doors including; a plurality of bearing brackets secured to the under side of said sill, a longitudinally arranged shaft mounted in said bearing brackets, link connections between said shaft and the doors on opposite sides of the center sill, said connections being self locked when the doors are in closed position, a transversely extending shaft, bearings secured to said center sill in which said shaft is mounted and in a plane

above the longitudinal shaft, a pair of winding drums on each of said shafts, and flexible connections between said drums.

5. In a hopper car having hinged doors and a center sill, an operating mechanism for said doors including; a plurality of bearing brackets secured to the underside of said sill, a longitudinally extending shaft mounted in said brackets, connections between said shaft and the hopper doors, a transversely extending operating shaft, brackets secured to the underside of said sill in which said shaft is mounted, drums on said operating shaft mounted between the brackets thereof, drums mounted on said longitudinal shaft and chain connections between said drums.

6. In a hopper car having hopper doors, the combination with channel center sills, a longitudinally extending shaft located below said sills, connections between said shaft and the doors, a transversely extending operating shaft, brackets secured to said channel sills in which said operating shaft is rotatably mounted, winding drums on said longitudinal shaft, winding drums on said operating shaft, and flexible connections between said drums, the drums on said operating shaft extending up between said channel sills.

7. The combination with a hopper car having a center sill and longitudinally arranged hoppers on each side of said sill, each hopper having an outwardly swinging door, of operating mechanism for said doors comprising a longitudinally extending shaft mounted in bearing brackets beneath said center sill, link connections between said shaft and the doors and which are self locked when the doors are in closed position, a transversely extending shaft operable from the side of the car and located in a plane above said longitudinal shaft, a pair of drums mounted on said operating shaft and located partly within the center sill, a pair of drums mounted on said longitudinal shaft, and flexible connections between said pairs of drums.

8. In a car having hinged doors, an operating mechanism for said doors including, a shaft, connections from said shaft to said doors, an operating shaft substantially at right angles to the first named shaft, and flexible connections between and attached to said shafts, said flexible connections winding about one shaft in planes substantially at right angles to the planes in which they wind about the other shaft.

9. In a car having hinged doors, an operating mechanism for said doors including, a shaft, connections from said shaft to said doors, an operating shaft at right angles to the first named shaft, and flexible connections between said shafts, said flexible connections winding about one shaft in

planes at right angles to the planes in which they wind about the other shaft, the portions of the flexible connections between the two shafts always extending vertically and remaining of constant lengths.

10. In a car door operating mechanism, the combination with an operating shaft extending transversely of the car from side to side, of means for locking and releasing said shaft operable from either side of the car, said means including a ratchet wheel on each end of said shaft, a pawl and a lock associated with each ratchet wheel, said pawls and locks being secured to the ends of transversely extending shafts, each of which is operable from either side of the car.

11. In a car door operating mechanism, the combination with an operating shaft extending transversely of the car from side to side, of means for locking and releasing said shaft operable from either side of the car, said means including a ratchet wheel on each end of said shaft, a pawl and a lock associated with each ratchet wheel, said pawls and locks being secured to the ends of transversely extending shafts each of which is operable from either side of the car, the operating shaft, the dog carrying shaft, and the lock carrying shaft being each provided with similarly shaped and sized ends whereby all of said shafts may be operated by the same tool.

12. In a door operating mechanism for dump cars, the combination with a shaft having a ratchet wheel thereon, of a pawl coöperating with said ratchet wheel and a lock coöperating with said pawl, said pawl and lock each having formed integrally therewith similar members, each member being adapted to detachably receive an operating tool whereby the same tool may be employed to operate both the pawl and the lock.

13. In an operating mechanism for dump car doors, the combination with an operating shaft extending transversely of the car from side to side thereof, of two other shafts extending transversely of the car from side to side thereof, one of said shafts being provided with pawls at each end thereof arranged to coöperate with said ratchet wheels, and the other of said shafts being provided with locking cams at each end thereof adapted to coöperate with said pawls, each of said pawls and locking cams being provided with an integral squared portion adapted to be operated by a claw bar or similar tool.

14. In a door operating mechanism of the character described, the combination with an operating shaft having a locking member on the end thereof, of means coöperating with said locking member to lock the

shaft in position, said means including a dog pivoted about an axis parallel with the axis of said shaft and coöperable with said locking member, and a locking cam engageable with said dog and pivoted about an axis parallel to said first named axes, said shaft, dog and cam being each provided with an integral squared portion, said squared portions being of the same size and thereby adapted to be actuated by the same claw bar or other operating tool.

15. A car having at each side of its longitudinal center hoppers with downwardly and outwardly inclined inner sheets, doors hinged at their upper ends at the side of the car for closing said hoppers, a longitudinal auxiliary operating shaft, crank and link connections connecting said shaft with the doors at the side of the car for opening and closing said doors, a transverse operating shaft to be operated manually, and means for imparting reverse motions from said transverse shaft to said longitudinal shaft for opening and closing the doors, said 25 means comprising a pair of wheels on said transverse shaft, a pair of wheels on said longitudinal shaft, and chains connecting the wheels on the transverse shaft with the wheels on the longitudinal shaft and so disposed that when the transverse shaft is rotated in one direction it will operate the longitudinal shaft to open the doors and when rotated in a reverse direction will impart a reverse rotation to said longitudinal shaft and compel the closing of the doors.

16. A car having at each side of its longitudinal center hoppers with downwardly and outwardly inclined inner sheets, doors hinged at their upper ends at the side of the car for closing said hoppers, a longitudinal auxiliary operating shaft, crank and link connections connecting said shaft with the doors at the side of the car for opening and closing said doors, a transverse operating shaft to be operated manually, and means for imparting reverse motions from said transverse shaft to said longitudinal shaft for opening and closing the doors, said means comprising a pair of parallel 40 wheels on said transverse shaft, a pair of parallel wheels on said longitudinal shaft standing at right angles to the wheels on the transverse shaft and below the same, and independent chains respectively, connecting the wheels on the transverse shaft with the wheels on the longitudinal shaft and being so disposed that when the transverse shaft is rotated in one direction one of the chains will rotate the longitudinal

60 shaft to compel the opening of the doors and when the transverse shaft is rotated in the opposite direction, the other chain will impart a reverse rotation to the longitudinal shaft and compel the closing of the doors.

65

17. A car having hinged discharge doors, an auxiliary operating shaft, crank and link connections connecting said shaft with the doors for opening and closing the same, a manually operative operating shaft, and means for imparting reverse motions from said operating shaft to said auxiliary shaft for opening and closing the doors, said means comprising a pair of wheels on said operating shaft, a pair of wheels on said 75 auxiliary shaft and chains connecting the wheels on one shaft with the wheels on the other shaft and so disposed that when the operating shaft is rotated in one direction it will rotate the auxiliary shaft to open 80 the doors and when rotated in a reverse direction will impart a reverse rotation to said auxiliary shaft and compel the closing of the doors.

18. In a car having a center sill and 85 hinged hopper doors, an operating mechanism for said doors including; a plurality of bearing brackets secured to the under side of said sill, a longitudinally arranged shaft mounted in said bearing brackets, 90 connections between said shafts and said doors, said connections being self-locked when the doors are in closed position, a transversely extending shaft, bearings secured to said center sill, in which said transverse shaft is mounted and in a plane above the longitudinal shaft, a pair of winding drums on each of said shafts, and flexible connections between said drums.

95

19. In a hopper car having hinged doors 100 and a center sill, an operating mechanism for said doors including; a plurality of bearing brackets secured to the under side of said sill, a longitudinally extending shaft mounted in said brackets, connections between said shaft and the hopper doors, a transversely extending operating shaft, brackets secured to the under side of said sill in which said transverse shaft is mounted, drums on said transverse operating shaft 105 located adjacent said brackets in which said transverse shaft is mounted, drums mounted on said longitudinal shaft, and chain connections between said drums.

105

110 In witness that I claim the foregoing I have hereunto subscribed my name this 13th day of August 1915.

ARGYLE CAMPBELL.
